M. S. BALDWIN,
ACCELERATOR DEVICE FOR AUTOMOBILES,
APPLICATION FILED DEC. 13, 1916.

Patented Apr. 17, 1917.

UNITED STATES PATENT OFFICE.

MORTON S. BALDWIN, OF ADRIAN, MICHIGAN.

ACCELERATOR DEVICE FOR AUTOMOBILES.

1,223,235.

Specification of Letters Patent. Patented Apr. 17, 1917.

Application filed December 13, 1916. Serial No. 136,685.

To all whom it may concern:

Be it known that I, MORTON S. BALDWIN, a citizen of the United States, residing at Adrian, in the county of Lenawee and State of Michigan, have invented certain new and useful Improvements in Accelerator Devices for Automobiles, of which the following is a specification.

This invention relates to the general subject of automobiles, and has particular reference to a novel improvement in foot-actuated accelerator devices for controlling the throttle valve of the carburetor.

To this end the invention contemplates a device of the character set forth, whereby the actuation of the throttle valve by the foot is entirely independent of the operation thereof by the hand throttle lever on the steering post, thereby giving the driver a selection of means for the control of the machine and also greater freedom of operation.

A further object of the invention is to provide a simple and practical device which is reliable and positive in its action and which is inexpensive to make, install and repair. In this connection it is proposed to provide a novel and reliable connection between the foot actuated element and the connection for the hand-throttle-operating means.

With the above and other objects in view which will more readily appear as the nature of the invention is better understood, the same consists in the novel construction, combination and arrangement of parts hereinafter more fully described, illustrated, and claimed.

A preferred and practical embodiment of the invention is shown in the accompanying drawings, in which—

Figure 1 is a plan view of an automobile showing the application of my invention.

Fig. 2 is a detail plan view more clearly illustrating my invention, and showing the normal position of the foot actuated element in full lines and the relation of the same to the hand throttle coupling rod when moved by the foot in dotted lines.

Fig. 3 is a detail sectional view of the novel one-way slip connection between the foot actuated accelerator element and the hand throttle coupling rod.

Similar references designate corresponding parts throughout the several figures of the drawings.

In carrying the present invention into effect it is not the purpose of the invention to alter or reconstruct the present devices provided for operating the throttle valve of the carburetor by hand, but to provide additional means whereby the throttle valve may be actuated by the foot of the driver of the machine entirely independent of the usual control by the hand device. By reference to Fig. 1 of the drawings, which shows in a more or less diagrammatic fashion the front portion of an automobile, it will be observed that the carburetor C is located at one side of the motor M, while the steering column S is located at the opposite side of the motor from the carburetor and projects up through the floor F of the machine, as shown. As usual, the steering column S has associated therewith the hand throttle stem A, which is connected to the throttle lever L of the carburetor by means of a coupling rod R. This coupling rod is pivotally connected to the hand throttle stem, and as will hereinafter more fully appear is not connected at its opposite end in the conventional manner with the throttle lever L, but has a special novel slip joint connection which forms an important part of the present invention and permits the movement of the throttle lever under the action of the foot accelerator device, without moving the hand throttle stem.

Referring now more particularly to the novel features of the accelerator device, it will be observed that the same essentially comprises an actuator plate 1, which as shown, is preferably of triangular shape, and rigidly attached as at 2 to the end of the short adjustment arm of the angular throttle valve lever L. Accordingly, it will be apparent that the said actuator plate 1 is rigidly fitted at one corner to a portion of the throttle operating member L while another corner thereof is secured to the end 100 of the long arm 3 of said member by means of the novel slip-joint unit U, whereby any movement of the actuator plate will shift the said throttle control member to thereby govern the opening and closing of the butterfly valve of the carburetor.

As will be observed from Fig. 3 of the drawings, this novel slip joint unit U preferably consists of a bolt 4 having thereon the nut 5, which clamps the end of the throttle arm 3 between itself and the underside of the plate, while the head of the bolt piv-

totally clamps a substantially U-shaped bracket element 6 to the upper face of the bolt. This bracket 6 is provided with aligned guide holes 7 for receiving the end of the 5 coupling rod R which is pivotally connected with the hand throttle stem A, and as will be seen from the drawings, the end portion 8 of this rod slidably extends through the 10 guide openings 7, and has its extremity provided with a plurality of pin-receiving openings 9, any one of which may receive a suitable pin or the like abutment 10. Thus with this type of connection between the 15 rod R and the plate a wide range of adjustment may be accurately accomplished, and as well known the feature of adjustment is extremely valuable in obtaining the proper mixtures of air and gas in carburetors.

With the pin 10 located at one side of the 20 walls of the bracket it will be apparent that any movement of the coupling rod R in the direction of the arrow, Fig. 3, will cause the movement of the throttle control element L and actuator plate 1. However, when the 25 actuator plate 1 is moved in the same direction by the operator's foot, the movement thereof will not affect the coupling rod R, as shown in dotted lines in Fig. 2, because of the location of the pins with relation to the 30 bracket and the operative directional movement of the rod R. Thus, it will be clear that the movement of the actuator plate 1 under foot pressure in the direction of the arrow shown in Fig. 2 and also Fig. 3, will 35 not cause any movement of the coupling rod, while on the other hand the movement of the coupling rod in the direction of the arrow will cause the combined movement of the actuator plate and throttle lever.

40 With further reference to the actuator plate 1, it will be observed that the same is connected as at 11 with the foot actuated push rod 12, which extends through a guide bushing B in the floor F of the machine, so 45 that the end thereof which projects beyond the floor may be conveniently provided with a cap or pedal element 13. At this point it may be also noted that for the purpose of enabling the operator to push the cap of the 50 rod 12 more readily, an arched foot rest bracket 14 may be provided on the floor of the machine adjacent the location of the cap or pedal. In order to maintain the actuator plate 1 in its normal position, that is, 55 so that the member L will cause the throttle valve to be closed or substantially so, there is provided a spring 15, one end of which is connected as at 16 to the hooked end of the push rod which engages with the opening 11 of the actuator plate, while the other end 17 thereof is attached to a suitable part of the machine, as clearly shown in Fig. 1 of the drawings.

From the foregoing, it is believed to be 60 apparent that upon imparting movement to

the push rod 12, the actuator plate 1 will move against the tension of the spring 15 to thus move the throttle lever, and because of the novel adjustable swivel slip joint connection between the end portion 8 of the coupling rod R and the plate, the said coupling rod will not be affected. When it is desired to control the throttle solely by hand, the movement of the usual hand throttle stem will pull the coupling rod R in the direction of the arrows in Figs. 2 and 3, and thus move the throttle control member L, and also the actuator plate 1 against the tension of the spring 15. Thus, the single spring returns and maintains the throttle lever in normal position regardless of whether or not it is moved by a foot actuated member or a hand actuated member.

Without further description, it is thought that the many novel and important features 85 of the present invention will be apparent, and it will, of course, be understood, that various changes in the form, proportion and minor details of construction may be resorted to without departing from the spirit 90 or the invention or scope of the appended claims.

I claim:

1. A foot actuated accelerator device for 95 automobiles including in combination with a carburetor having a throttle lever and a hand-controlled throttle stem, an actuator plate carried by said throttle lever, a foot actuated push rod connected with said plate, a spring for holding said plate in a normal 10 position, a swivel bracket element carried by said plate, and a coupling rod pivotally connected at one end to said hand-controlled stem and having its free end engaging said swivel bracket element on the actuator plate. 10

2. A foot actuated accelerator device for 11 automobiles including in combination with a carburetor having a throttle lever and a hand-controlled throttle stem, an actuator plate carried by said throttle lever, a foot actuated push rod connected with said plate, a spring for holding said plate in a normal 11 position, a swivel bracket element carried by said plate at its point of connection with the long arm of the throttle lever, and a coupling rod pivotally connected at one end to said hand-controlled stem and having its free end engaging said swivel bracket element on the actuator plate. 11

3. A foot accelerator device for 12 automobiles including in combination with a carburetor having a throttle lever and a hand-controlled throttle stem, a substantially triangular actuator plate carried by the throttle lever, a foot actuated push rod connected 12 with said plate, a spring for holding said plate in normal position, a swivel bracket element carried by said plate and connecting the same with the throttle lever, said swivel bracket including a bolt for pivotally clamp- 13

ing the long arm of the unthrottle lever to the underside of the plate and also pivotally clamping a substantially U-shaped bracket to the upper surface of said actuator plate, 5 and a coupling rod having one end pivotally connected with the hand throttle stem and having its other end projecting through guide openings of the swivel bracket, and a pin carried by said coupling rod for engaging 10 the bracket when moving in one direction.

4. A foot accelerator device for automobiles including in combination with a carburetor having a throttle lever and a hand-controlled throttle stem therefor, a spring-controlled actuator plate carried by said throttle lever, a foot actuated push rod connected with said actuator plate, a swivel bracket element carried by said plate and including a bolt for loosely clamping the long arm of the throttle lever to the underside of said plate and also loosely clamping the substantially U-shaped bracket portion to the upper side of said plate, said bracket portion having openings therein; a coupling rod connected with said hand-controlled stem at one end and having its opposite end working in the guide openings of said bracket, said rod having a portion thereof projecting be-

yond the bracket in its normal condition 30 and provided with a plurality of adjustment openings, and a pin for entering in one of said adjustment openings, whereby the movement of the rod moves the actuator plate, but the movement of the plate causes 5 the bracket to slide on the rod.

5. A foot actuated accelerator device for automobiles including in combination with a carburetor having a throttle lever and a hand-controlled stem therefor, an actuator plate carried by said throttle lever, a foot actuated connection for said plate, a spring for holding said plate in clamped position, a swivel bracket element carried by said plate, a coupling rod pivotally connected at 45 one end to said hand controlled stem, and having its free end engaging said swivel bracket element, and means for providing for relative adjustment between the free end of the coupling rod and the swivel bracket 50 element.

In testimony whereof I hereunto affix my signature in the presence of two witnesses.

MORTON S. BALDWIN.
